UNITED STATES PATENT OFFICE.

LEWIS H. NASH, OF SOUTH NORWALK, CONNECTICUT, ASSIGNOR TO NATIONAL METER COMPANY, OF NEW YORK, N. Y., A CORPORATION OF NEW YORK.

MIXER AND GOVERNOR FOR GAS-ENGINES.

SPECIFICATION forming part of Letters Patent No. 760,750, dated May 24, 1904.

Application filed March 13, 1900. Serial No. 8,527. (No model.)

To all whom it may concern:

Be it known that I, LEWIS H. NASH, a citizen of the United States, and a resident of South Norwalk, in the county of Fairfield and State of Connecticut, (whose post-office address is 47 Elmwood avenue, South Norwalk,) have invented a new and Improved Mixer and Governor for Gas-Engines, of which the following is a full, clear, and exact description.

10 My invention relates to an improvement in devices for controlling the proportions of air and gas as supplied to gas-engines and also to controlling the amount of such mixture supplied to the engine, and comprises the 15 novel features which will be hereinafter described, and particularly pointed out in the claims.

Reference is to be had to the accompanying drawings, forming a part of this specification, 20 in which similar characters of reference indicate corresponding parts in all the figures.

Figure 1 is a sectional elevation of my device shown attached to the frame of an engine, the section being upon the line 1 1 of 25 Fig. 2. Fig. 2 is a sectional elevation upon the line 2 2 of Fig. 1. Fig. 3 is a sectional plan view taken on the line 3 3 of Fig. 2, and Fig. 4 is a sectional elevation taken upon the line 4 4 of Fig. 2.

30 The object of my invention is to provide a device which may be adjusted to accurately control the proportions of air and gas supplied to the engine and at the same time to control the amount of such mixture which is supplied, 35 and thus to control the speed of the engine. A form of construction by which this result is obtained is shown in the accompanying drawings, which, with the accompanying description, are given to illustrate my invention 40 in a concrete form, as is required. The mechanism herein shown and described is not, however, presented as the only possible means by which my invention may be carried out, but only as a means now adopted by me.

45 In Fig. 1 a portion of the frame of an engine is shown at A to which my device is attached. The mechanism for controlling the mixture is contained within a case B. This

case has a chamber G formed therein, to which the gas-supply pipe is attached, Fig. 3. The 50 chamber E is in communication by one end with the chamber G, from which it receives gas. The opposite end of the chamber E is in communication by its open end with a chamber D', which is a continuation of or connected 55 with a chamber D, to which the air-supply connection is made. The cylindrical chamber E is thus in communication at opposite ends, respectively, with the gas and air supply. Within the body of the case B is formed a chamber 60 K, which is in communication with the chamber E by means of a long and narrow port, which is herein shown as rectangular in outline, although this may be of other forms. The chamber K is in communication with ports C and C', 65 through which the mixed air and gas is conveyed to the engine cylinder or cylinders. The air-supply chamber D is also in direct communication with the chamber K by means of a port d, which is opposite the port e, 70 and preferably of the same size therewith. The two opposite faces of the chamber K, within which the two ports e and d are formed, are parallel with each other, forming valve-seats. Within this space and in close 75 contact with both of these faces is a valve H, which may be moved so as to more or less close the ports e and d. This valve is herein shown as being pivoted at one end upon a reduced section h', projecting eccentrically 80 from a pin h'', which extends to the outside of the case and is provided with a screw-slot or other device by which it may be turned. The end of the valve opposite its pivot is supported upon and moved by a rod I, which extends through the wall of the case B and is acted upon by a governor J of any suitable construction. The valve H does not entirely 85 fill the space between the walls of the chamber K, but permits the passage of the air and gas about its ends to beneath the same, so that the valve is not influenced by the pressure or suction of the gas. The valve is herein shown as having holes h passing through the same, thus affording free communication 90 between opposite sides thereof.

Within the cylinder E is a partition or piston F, which is carried upon a rod F', the latter passing through a suitable stuffing-box in the case and being provided with a knob or 5 other suitable means exterior to the case, whereby the piston or diaphragm F may be adjusted in position in the cylinder E. In Fig. 4 the rod F' is not shown, as it would cover the port e. The center of the main section h² of the valve pivot-pin is preferably on the line of the top of the ports e and d, and the center of the section h' in line with the top edge of the valve, so that by turning the pin so as to raise or lower the end h', the 10 proportion of gas and air may be varied by the governor acting under the influence of light and heavy load. If the pivot is raised, the proportion of gas will be reduced under light load, and if it is lowered the proportion 15 of gas will be increased under light load. This is due to the fact that with the valve-pivot h' on the line of the top edges of both valve and ports the port-openings remain triangles, and consequently wherever the partition F may be the relative areas of the port-divisions thereby made remain constant.

The operation of my device is as follows: Air which is introduced to the chamber D passes through the port d into the chamber 30 K, being controlled in amount somewhat by the valve H. The air also enters the end E' of the cylinder E and passes through that portion of the port e lying between the piston or diaphragm F and that end of the cylinder. This area will vary with the position 35 of the piston or diaphragm. Gas entering the chamber G will enter the end E² of the cylinder E and pass through that portion of the port e lying between that end of the cylinder and the position of the piston or diaphragm F. By adjusting the position of this diaphragm in the cylinder the proportion of 40 air and gas supplied will be varied. It will thus be seen that the proportionate area of the air and gas supply ports may be adjusted to accommodate the device to varying conditions. For instance, if the quality of the gas should vary the position of the diaphragm might be adjusted so as to change the proportion of the gas used. It would also be 45 possible to adjust the position of the diaphragm to accommodate the device to different relative pressures of gas and air. The action of the governor in raising or lowering 50 the valve H will when the valve-pivot is on the line of the top edges of the valve and ports maintain the gas and air supply port areas at substantially the same ratio at all 55 positions of the valve. This is due to the fact that the valve operates in identically the same manner upon both ports and both portions of the port, which are common to the gas and air supply. The rod F', which is connected with 60 the piston or diaphragm F and by which it is moved, may be provided with a scale upon

its outer portion, by which the position and the proportionate mixture of the air and gas may be changed. The gas being admitted through a port opposite an air-admission port, so that the incoming jets of air and gas are directed directly toward and impinge upon each other, a whirling action is at once set up which thoroughly mixes the two, thus promoting the perfect combustion of the gas.

Having thus fully described my invention, I 75 claim as new and desire to secure by Letters Patent—

1. A mixing device for gas-engines, having a port provided respectively with air and gas supply connections at opposite ends thereof, 80 and a common air and gas discharge port and a movable member controlling the division of said port between the air and gas supply, substantially as described.

2. A mixing device for gas-engines containing a chamber having air and gas supply connections to opposite ends thereof, and a common air and gas discharge port, and a piston or diaphragm movable in said chamber to control the division of said port between the 85 air and gas supply.

3. A mixing device for gas-engines, containing a cylinder having air and gas supply connections with opposite ends thereof and a common air and gas discharge port in its side, and a piston or diaphragm movable lengthwise 95 said cylinder to control the division of the port between the air and gas, substantially as described.

4. An air and gas mixing device for gas-engines, having air and gas supply ports directly opposite of and facing each other, whereby their jets are directly commingled, a 100 governor, and means for proportionately controlling the opening of said ports by said governor, substantially as described.

5. An air and gas mixing device for gas-engines, having air and gas supply ports facing each other, whereby their jets are directly commingled, a common controlling-valve for said 105 ports, and a governor connected with said valve to move it, substantially as described.

6. An air and gas mixing device for gas-engines containing parallel faces or walls having 110 therein air and gas supply ports located respectively in opposing faces to directly commingle the air and gas jets, a valve moving between said faces to control the port areas, and a governor connected with the said valve, substantially as described.

7. An air and gas mixing device for gas-engines containing parallel faces or walls having 115 therein respectively air and gas supply ports, located respectively in opposite walls whereby the jets from air and gas ports discharge into each other, a valve movable between said faces to control the port areas, and a governor connected with and controlling the said valve, substantially as described.

8. An air and gas mixing device for gas-en- 120

gines provided with air and gas supply ports, a valve controlling the opening of both of said ports, a governor connected with and controlling the amount of opening of said valve, and means for adjusting said valve to vary the proportionate openings of the gas and air ports at different positions of the valve, substantially as described.

9. An air and gas mixing device for gas-engines provided with air and gas supply ports, a valve controlling the opening of both of said ports, and means for adjusting said valve to vary the proportionate openings of gas and air ports at different positions of the valve, substantially as described.

10. An air and gas mixing device for gas-engines provided with air and gas supply ports, a valve controlling the opening of both of said ports, a governor connected with and controlling the amount of opening of said valve, and means for adjusting said valve to vary the proportionate openings of gas and air ports at different positions of the valve, and independent means for controlling the proportionate areas of air and gas supply ports, substantially as described.

11. An air and gas mixing device for gas-engines provided with air and gas supply ports, a valve controlling the opening of both of said ports, and means for adjusting said valve to vary the proportionate port-openings as between the gas and air supply at different positions of the valve, and independent means for controlling the proportionate areas of air and gas supply ports, substantially as described.

12. An air and gas mixing device for gas-engines provided with a port having air and gas supply connections respectively with opposite ends thereof, a movable member controlling the division of said port between the air and gas supply, a valve controlling the opening of said port, and a governor controlling said valve, substantially as described.

13. An air and gas mixing device for gas-engines provided with a port having air and gas supply connections respectively with opposite ends thereof, a movable member controlling the division of said port between the air and gas supply, a valve controlling the opening of said port, a governor controlling said valve, and means for adjusting said valve to vary the proportionate openings of the air and gas portions of said port at different positions of the valve, substantially as described.

14. An air and gas mixing device for gas-engines having air and gas supply ports and a common controlling-valve therefor pivoted at one end, said ports being arranged at different distances from said pivot, substantially as described.

15. An air and gas mixing device for gas-engines having air and gas supply ports and a common controlling-valve therefor pivoted at one end, said ports being arranged at different distances from said pivot, and means

for varying the relation of the pivot-point and the margin of the port, substantially as described.

16. An air and gas mixing device for gas-engines, having air and gas supply ports, a common controlling-valve therefor, and an eccentric pivot-pin for one end of said valve, said air and gas ports, being at different distances from the pivot, substantially as described.

17. An air and gas mixing device for gas-engines, having air and gas supply ports and a common controlling-valve therefor pivoted at one end, said ports being arranged at different distances from said pivot, and a governor connected with said valve to move it, substantially as described.

18. An air and gas mixing device for gas-engines, having air and gas supply ports, a common controlling-valve therefor, and an eccentric pivot-pin for one end of said valve, said air and gas ports, being at different distances from the pivot, and a governor connected with said valve to move it, substantially as described.

19. An air and gas mixing device for gas-engines provided with a port having air and gas supply connections respectively with opposite ends thereof, a movable member controlling the division of said port between the air and gas supply, a valve controlling the opening of said port, and an eccentric pivot-pin for one end of said valve whereby its pivot end may be adjusted laterally of the direction of the ports, substantially as described.

20. A mixing device for gas-engines having a port through different portions of which both air and gas are admitted to the engine, and adjustable means for dividing said port between the air and gas supply.

21. A mixing device for gas-engines having a common air and gas supply port, and means for varying the proportionate area of said port used respectively for the gas and for the air supply.

22. A mixing device for gas-engines having a common air and gas supply port, adjustable means for dividing said port between the air and the gas supply, and independent means for varying the proportionate opening of the gas and air supply portions of said port according to a predetermined ratio.

23. A mixing device for gas-engines having a common air and gas supply port, means for dividing said port between the air and the gas supply, and means for controlling the opening of said port to vary the ratio between the air and the gas supply portions thereof at different openings.

24. A mixing device for gas-engines having a common air and gas supply port, means for dividing said port between the air and the gas supply, a valve controlling the opening of said port, and means for varying the action of said

valve to control the proportionate area of air and gas supply portions of the port either at a constant or a variable ratio at different openings of the port.

5 25. A mixing device for gas-engines having air and gas supply ports, a valve controlling the effective area of said ports, means for adjusting the proportionate area of the ports available for the air and gas supply, and means 10 for operating the valve to control the proportionate area of the air and gas supply ports either at a constant or a variable ratio at different openings of the port.

26. A mixing device for gas-engines having 15 a common air and gas supply port, and adjustable means for dividing said port between the air and the gas supply without altering the area of the port.

27. A mixing device for gas-engines having 20 a common air and gas supply port, adjustable means for dividing said port between the air and the gas supply without altering the area of the port, and independent means for varying the opening of said port.

25 28. A mixing device for gas-engines comprising a chamber having a port in its walls through which both air and gas are admitted to the engine, and adjustable means for divid-

ing said port between the air and the gas supply.

30

29. The combination in a charge-controlling mechanism for explosion-engines, of a governor and means operated by said governor for controlling the quantity of the charge in accordance with the speed of the engine, and 35 means for adjusting the charge-controlling mechanism so that said governor also varies the richness of the charge at different cut-offs in either way from a constant ratio.

30. In a fuel-mixing device, the combination 40 of an air-supply, a gas-supply, a volume-controlling device having a member provided with a port, and a partition or separating member arranged between the air-supply and the gas-supply adjacent to said port, one of said members being adjustable with reference to the other for varying the proportions of air and gas, substantially as described.

In testimony whereof I have signed my name to this specification in the presence of the two 45 50 subscribing witnesses.
